(57) **CLAIM**

The ornamental design for a Roman shade having spacer cords with loops, as shown and described.

DESCRIPTION

FIG. 1 is a front view of the Roman shade having spacer cords with loops in a partially raised, or retracted, position;

FIG. 2 is a rear view of the Roman shade having spacer cords with loops in a partially raised, or retracted, position;

FIG. 3 is a rear perspective view of the Roman shade having spacer cords with loops in an extended, or lowered, position;

FIG. 4 is a top view thereof;

FIG. 5 is a bottom view thereof;

FIG. 6 is a left side view of the Roman shade having spacer cords with loops in an extended position;

FIG. 7 is a right side view of the Roman shade having spacer cords with loops in an extended position; and,

FIG. 8 is an enlarged view of the portion of the Roman shade having spacer cords with loops within the dotted line box in FIG. 2.

It should be understood that the Roman shade having spacer cords with loops may be any width and any length when fully extended.
